CLAIM

The ornamental design for a cutting board, as shown and described.

DESCRIPTION

FIG. 1 is an isometric view of a cutting board showing our new design.

FIG. 2 is a left side view thereof.

FIG. 3 is a top view thereof.

FIG. 4 is a front view thereof.

FIG. 5 is a back view thereof.

FIG. 6 is a bottom view thereof; and,

FIG. 7 is a right side view thereof.

The broken lines shown in the drawings are for illustrative purposes only and form no part of the claimed design.
